UNITED STATES PATENT OFFICE

2,519,875

STRAIGHT KNITTING MACHINE

Emil J. Berger and Howard K. West, Lansdale, Pa., assignors to Dexdale Hosiery Mills, Lansdale, Pa., a corporation of Pennsylvania

Application February 12, 1948, Serial No. 7,807

7 Claims. (Cl. 66—82)

1

This invention relates to knitting machines, and has reference more specifically to straight stocking knitting machines of the type disclosed in U. S. Patent No. 2,331,528 granted to Howard K. West, one of the present applicants, on October 12, 1943, wherein a series of cover points cooperate with beard-less hook needles in stitch formation.

In connection with a machine of the kind referred to, we aim to provide mechanism whereby, upon starting of the machine, a welt bar is automatically positioned in operative relation to the needles to receive the first course of the knitting, and after its hooks have engaged the loops of such course, released to the pull of a yielding draw off means; and mechanism whereby the actuating means for the cover points is rendered inactive with said points positioned out of the way of the needles and of the hooks of the welt bar during formation of the initial course of the knitting.

A further aim of our invention is to provide for the automatic retraction of the cover points from its normal operative relation to the needles as the cam shaft is shifted in the narrowing phases of the knitting when loop transfer between adjacent needles is to take place.

Another object of our invention is to minimize frictional action of the stitch forming instrumentalities upon the knitting yarns to reduce chaffing and ruptures, and thereby enable the operation of the machines at higher speeds and the employment of much finer yarns than heretofore practicable.

How the foregoing and other important advantages are realized in practice will appear from the following detailed description of the attached drawings wherein, Fig. 1 is a view in front elevation of a straight knitting machine conveniently embodying our invention.

Fig. 2 shows the machine in top plan.

Fig. 3 is a broken out view in plan like Fig. 2 with certain parts omitted to expose parts which would otherwise be concealed.

Fig. 4 is a cross sectional view of a machine taken as indicated by the angled arrows IV—IV in Figs. 1 and 2.

Figs. 5 and 6 are cross sectional views like Fig. 4 with various parts differently positioned.

Figs. 7 and 8 are fragmentary views in cross section corresponding to Figs. 5 and 6 with certain parts in still other positions.

Fig. 9 is a cross section like Figs. 4—6 showing how the cover points are withdrawn during the fashioning phases of the knitting.

2

Fig. 10 is a cross section taken as indicated by the angled arrows X—X in Fig. 1 showing the welt bar positioned in readiness to receive the initial course of the knitting.

Fig. 11 is a fragmentary broken out view in plan looking as indicated by the angled arrows XI—XI in Fig. 10.

Fig. 12 is a detailed section taken as indicated by the angled arrows XII—XII in Fig. 11.

Fig. 13 is a view in plan like Fig. 11 showing the welt bar with its hooks engaging the initial course of the knitting.

Fig. 14 is a detail view in cross section taken as indicated by the angled arrows XIV—XIV in Fig. 13.

Fig. 15 is a fragmentary detail view in end elevation looking as indicated by the angled arrows XV—XV in Figs. 1 and 2.

Fig. 16 is a detail section taken as indicated by the angled arrows XVI—XVI in Figs. 1 and 2.

Figs. 17, 18 and 19 are detail views in section taken as indicated respectively by the angled arrows XVII—XVII, XVIII—XVIII and XIX—XIX in Figs. 2, 15 and 16.

Fig. 20 is an enlarged fragmentary detail cross section showing the cooperative stitch forming elements of our improved machine.

Fig. 21 is a fragmentary view in elevation looking as indicated by the angled arrows XXI—XXI in Fig. 20.

Fig. 22 is a fragmentary view in horizontal section taken as indicated by the angled arrows XXII—XXII in Fig. 21; and

Figs. 23—28 are fragmentary sectional views like Fig. 20 showing the stitch forming elements in successive positions which they assume during a stitch forming cycle.

The needle bar 30 of the illustrated machine is actuated, through interposed connections (not shown), from the cam shaft indicated at 31, the needles 32 having the form of hooks as in the West patent hereinbefore mentioned. Cooperative with the needles in the formation of the fabric loops are butted sinkers 33 and auxiliary butted sinkers or dividers 34 which are slidable horizontally in individual transverse slots of the sinker head 35, and therein retained by the usual verge plate 36 and knockovers 37 which are anchored in a bar 38 adapted to be actuated in the usual way through interposed connections (not shown) from the cam shaft 31. Also as in the West patent supra, individual cover points 39 serve in lieu of the usual spring beards of the needles, these being secured in a separate bar 40 with supporting arms 41 at

opposite ends thereof fulcrumed on studs 42 projecting laterally from slides 43. At their bottoms, the arms 41 have arcuate notches 44 in concentric relation to the fulcrum studs 42 to clear stop pins 45 on upwardly and inwardly extending extensions 43a of the slides 43. By virtue of this construction, the point bar 40 can be swung upwardly and outwardly as indicated in dot and dash lines in Fig. 5 when access to the needles is desired or necessary. By means of set screws 46 arranged to contact the pins 45, it is possible to accurately adjust the operative level of the points 39 relative to the needles as will be readily seen from Fig. 14. The slides 43 are confined to endwise movement in sleeve guides 47 which are fulcrumed on a horizontal rock shaft 48 whereof the ends are journaled in the side frames 50 of the machine. In accordance with our invention, the slides 43 are connected by a horizontal tie bar 51 whereof the opposite ends are secured, as instanced in Figs. 16 and 18, by screws 52 to blocks 53 pendant from said slides through clearance slots 54 in the bottoms of the guides 47. The spring belts shown at 55 in Figs. 2 and 3 have their ends secured at 56 to the tie bar 51 and are trained about pulleys 57 on the front bed 58 connecting the side frames 50 at the top to urge the slides 43 inward of the machine and so maintain rollers 59 free on the studs 42 of the slides engaged with upstanding cam projections 60. In accordance with our invention the projections 60 are secured, with capacity for adjustment, to the tops of the side frames 50. As shown, the cam projections 60 have horizontal portions 60a which, see Figs. 15 and 19 are slotted as at 61 for passage of the shanks of cap screws 62 which take laterally into the side frames 50. Adjustment is facilitated by means of set screws 63 which are threaded into lugs 64 affixed to the side frames and which bear against the rear edges of the horizontal portions 60a of the cam projections 60 as best seen in Fig. 15.

Clamped to the rock shaft 48 (Figs. 1-6) is a pendant arm 65 with a roller 66 thereon adapted to run in contact with the periphery of a rotary cam 67 on the cam shaft 31 during ordinary knitting, and in contact with the periphery of an adjacent cam 68 when said shaft is shifted toward the observer in Figs. 4-6 for narrowing. A spring 70 pulls upon the arm 65 to keep the roller 66 yieldingly engaged with the cam 67 or the disk 68 as the case may be. Thus by action of the parts just described, the rock shaft 48 is oscillated with consequent impartation of up and down movements to the cover point bar 40. As shown, the arm 65 is formed in two sections 65a and 65b which are connected by a knuckle joint with the pivot as 71. The lower end of the section 65a is slotted as at 72 to receive the upper end of section 65b, and the two are yieldingly held in the normal relation in which they are illustrated in Figs. 4, 5 and 7 by a spring 70. However, this relation of the sections 65a and 65b can be varied slightly to change the angularity of the guides 47 and hence of the slides 43 by adjustment of a set screw 73 which is threaded into the section 65a and which engages the section 65b somewhat above the pivot 71 as shown.

The required outward movements are imparted to the point bar 40 through mechanism including a lever 75 which is fulcrumed at 76 on a bearing bracket 77 affixed at its top to the bed 58 and at the bottom to a supplemental frame member 78. The upper arm of lever 75

contacts a roller 80 supported by a plate 81 which is clamped between the bar 51 connecting the two guides 47 and to a block 82 (see Figs. 2 and 17), which is notched laterally to freely engage the rock shaft 48. The bar 51 is apertured and the plate 81 slotted as at 83 for passage of the shanks of cap screws 84 which take into the block 82. It is thus possible to adjust the roller 80 relative to the guides 47, such adjustment being facilitated by a set screw 85 which is threaded into the block 82 from the front and which bears against the rear edge of the plate 81. The lower arm of lever 75 carries a roller 86 wherewith contacts the upper arm of another lever 87 with fulcrum support at 88 on supplemental frame 78, the lower arm of the latter lever in turn carrying a roller 90 which is adapted normally to run on a circular idling disk 91 on cam shaft 31. When the cam shaft 31 is shifted endwise for fashioning, another rotary cam 92 thereon is brought into the plane of the roller 90 to actuate the lever 87 with resultant impartation of outward movement to the slides 43 through the medium of the lever 75 as and for a purpose later explained. The spring shown at 93 acts upon the lever 87 to maintain the roller 90 in engagement either with the disk 91 or the cam 92 as the case may be.

From Figs. 1 and 4-8 it will be observed that a lug 95 projects laterally from the sections 65a of lever 65 immediately above the pivot 71, which lug during the normal operation of said arm avoids the nose of a trip element 96 pivoted on the bracket 77. By means of a link 97, the trip element 96 is coupled with a short arm 98 affixed to another rock shaft 99 in the upper frontal part of the machine. A second short arm 100 (see also Fig. 10) is in turn coupled by another link 101 with a spring-biased finger 102 on a rock shaft 103 in the lower frontal part of the machine adjacent a shaft 104. This shaft 104 carries a cam drum 105 with ratchet teeth 106 arranged to be picked intermittently by pawling mechanism (not shown), said drum being provided with a cam projection 107 for actuating the finger 102 as hereinafter noted.

In accordance with our invention, the shanks of the needles 32 are swaged as at 32a and thereby spread to a width (see Figs. 21 and 22) substantially equal to that of the intervals between adjacent sinkers 33 and dividers 34, and incidentally hollowed out for a considerable distance for capacity to receive the tips of the points 39 incident to stitch formation. The sinkers 33 (Fig. 20) have yarn receiving throats 33a but are devoid of the usual forward tongue projections at the bottom and terminate at their front ends in substantially vertical edges 33b. The dividers 34 likewise have upper yarn receiving throats at 34a, but are devoid of the usual upper nibs and are further characterized by straight and substantially vertical edges 34b between said receiving throats and the usual lower throats 34c. As usual, however, the dividers 34 have forwardly projecting tongues 34d at the bottom. The points 39 are longitudinally fluted as at 39 and, like the swaged portions 32 of the needle shanks, are made to a width substantially equal to that of the intervals between adjacent sinkers and dividers. The purpose and advantages of these special constructions will also be later brought out.

In order to facilitate application of the welt bar 109 (Figs. 10-13) for engagement of its hooks 110 with the starting course of each stocking blank, the machine is provided with supporting

rails 111 which are screwed fast to the bed 58. Forwardly projecting skids 112 attached to end extensions 109a of the welt bar 109 at the bottom are adapted to rest on the rails 111 and, as shown, are tapered in cross section to determine slight downward tilting of the welt hooks 110. By co-operation with the end extensions 109a of the welt bar 109, fixed guards 114 along the outer sides of the rails 111, assist in guiding said bar as it is slid inwards of the machine toward the needles 32 as far as permitted by engagement of said end extensions with upstanding stop projections 115a of a pair of retracting elements 115 which are disposed longitudinally of the outer sides of said rails between the latter and the guards. The elements 115 are constrained to endwise movement in slots 116 formed in lateral projections 111a, 111b of the rails 111 see Figs. 11 and 12, and are yieldingly drawn outward by tension springs 117. Outward movement of the elements 115 is limited by engagement of stop shoulders 115b thereon with the lateral projections 111a of the rails 111.

The welt bar 109 is automatically moved into operative position as in Fig. 10 relative to the needles 32 by means including a pair of thrust elements in the form of bars 120 which are arranged longitudinally of the inner sides of the rails 111 and normally rest on top of the bed 58 as shown in Fig. 14 with stop shoulders 120a at their bottom edges engaged with the inner edge of said bed. The outer ends of the thrust bars 120 are pivotally connected at 121 to arms 122 fixed to another rock shaft 123 which has rotative support in fixed bearing brackets 124 on the bed 58. Also affixed to the shaft 123 is a crank arm 125 from which a hook element 126 is hung. The spring at 127 tends to keep the hook element 126 normally withdrawn from the path of a lateral stud 128 on the arm 130a of a lever 130 medially fulcrumed on a fixed center 131. The lever 130 is subject to a spring 132 and its other arm 130b carries a roller 133 arranged to be acted upon by another rotary cam 134 on cam shaft 31. Upon movement of the shaft 99 counterclockwise, a spring finger 135 thereon by cooperation with a pin 136 on the hook element 126 swings said element inward to engage with the stud 128 of lever 130. Thus, as the lever 130 is actuated by the cam 134, the bars 120 are thrust inward as in Fig. 10 with the result that by coaction of sloped cam notches at 120b with fixed studs 137 extending laterally from the rails 111, the forward ends of said bars are raised to engage the end projections 109a of the welt bar 109 from behind. As the movement continues, the welt bar 109 is pushed inward until the welt hooks 110 are positioned between the needles 32 in readiness to receive the first courses of fabric loops drawn by said needles. During the advance of the welt bar 109, a spring finger 138 disposes the inner end of the adjacent thrust bar 120 which in turn contacts one end of the welt bar 109 and shifts the latter so that the other end thereof bears against the contiguous guard 114 as in Fig. 11. In this way, the hooks 110 of the welt bar are accurately positioned on center with the intervals between the needles 32. Each thrust bar 120 is provided with a flexible projection 139 arranged to react with the corresponding stud 137 to limit the rise of the bar as it is thrust forward.

Operation

In preparation for the knitting of a stocking blank, the welt bar 109 is slid inwardly on the rails 111 by hand until it is intercepted by en-

counter of its end projections with the stops 115a of the retracting elements 115 which are normally held fully withdrawn by the springs 117. In being so placed, the guards 114 serve as guides to approximately center the welt bar on the rails 111 in a manner which will be readily understood from Figs. 11 and 13 of the drawings. The machine is thereupon started and the thrust bars 120 moved inward when the ratchet wheel 106 is pawled to advance the cam rise 107 on drum 105 beneath the finger 102 as in Fig. 5. In consequence, the finger 102 is raised and through the link 101 and the arm 100 causes impartation of a partial anti-clockwise movement to the shaft 99 which is attended by actuation of the flexible finger 135 to shift the hook element 126 into the path of the stud 128 on the lever 130. Upon actuation of the lever 130 by the rotary cam 134, the hook element 126 is drawn downward and, through the arms 125 and 122 on shaft 123, causes the thrust bars 120 to be moved inward, with attendant advance of the welt bar 109 to the position in which it is shown in Fig. 10. Lifting of the finger 102 by the rise 107 on drum 105 as just explained, is also attended by clockwise turning of the trip element 96 from the normal position of Fig. 4 to the position of Fig. 5. Consequently, when the arm 65 is moved by encounter of the hump 67a of rotary cam 67 with the roller 66, the projection 95 on the section 65a of said arm is brought into contact with the trip element 96 as in Figs. 6 and 8 to detain the upper section 65a of said arm and so prevent operation of the point bar 49 which will therefore remain inactive in raised position out of the range of the needles 32. Before completion of the current rotation of cam shaft 31, the needles 32, the sinkers 33 and the dividers 34 will be operated and the initial course C of the stocking blank formed over the hooks 110 of the welt bar as in Figs. 10 and 11 whereupon the ratchet 106 is again picked and the drum 105 rotatively shifted for advancement of its cam lug 107 from beneath the finger 102. As the finger 102 drops, the shaft 99 will be reversely turned with resultant retraction of the flexible tongue 135 from the hook element 126 and the latter withdrawn from the stud 128 of the roller arm 130 by the spring 127, whereby the trip element 96 is restored to its normal position as in Fig. 4. The spring 70 thereupon immediately acts to re-set the sections 65a and 65b of the roller arm 65 in their normal relationship in which they are illustrated in Fig. 4. During the reverse turn of the shaft 99 as above, the thrust bars 120 are restored to the normal position of Fig. 14 by influence of the spring 127 on arm 122, and the welt bar 109 released to the action of retracting elements 115. By the pull of the springs 117 upon the elements 115, the welt bar 109 is drawn outward with its hooks engaging the course C as in Figs. 13 and 14. From then on the knitting proceeds normally until sufficient fabric for the welt of a stocking has been knitted, whereupon the machine is stopped for turning of the welt in the usual way. However, at some time during the early stages of this phase of the knitting, the attendant is obliged to connect the usual take up straps 140 (Fig. 13) to the welt bar 109 before the shoulders 115b on the detents 115 reach the lateral extensions 111a of the rails 111.

In normal knitting, the needle bar 38 is moved up and down and in and out relative to the sinkers and dividers during single rotations of the cam shaft 31 in exactly the same manner as

set forth in the West patent. The guides 47 are concurrently rocked about the shaft 48 as a center to raise and lower the cover point bar 40 by action of the rotary cam 67 upon the roller arm 65. At the same time, the slides 43 which carry the cover point bar 40 are reciprocated longitudinally through the medium of the part 75 by action of the rotary cam 91 upon the roller arm 87. In Fig. 20, the cover points 39 are elevated to the maximum extent, the knock-overs 37 fully retracted, the needles 32 fully raised and the sinkers 33 fully advanced to sink freshly fed yarn Y between alternate needles. With the needles still high, the cover points 39 descend to the position of Fig. 23. In Fig. 24, the dividers 34 have been advanced to further apportion the yarn Y between the needles 32 and the latter moved laterally into pressure contact with the cover points 39. In Fig. 25, the needles and the cover points 39 are moving down together in contact with each other and at the same rate, the points passing down through the loops of a previously formed fabric course on the needles with the sinkers and dividers still advanced and the kinks of the freshly fed yarn Y still held in the sinker and divider throats. In Fig. 26 the sinkers and dividers are fully retracted while the needles are still moving down and receding from the cover points 39 which have begun to rise. Fig. 27 shows the needles 32 all the way down with the loops of the freshly laid yarn drawn through the loops of initial course C still restrained by the points which continue upward, with concurrent advance of the knock-overs 37. Fig. 28 shows the completion of the stitch forming cycle with the loops of the new fabric course pushed over the tops of the needles by the knock-overs 37. It is to be particularly noted that at no time do the cover points 39 engage the usual presser edge at 35a, pressure contact between the needles and the points during the stitch formation being maintained through mutual yielding of these elements made possible by their inherent flexibility and novel construction. It is to be especially noted further that while the sinkers 33 are being advanced, they are steadied by reason of the presence of the thickened portions of the needle shanks and of the points 34 between them and the tongues of the dividers as best seen in Figs. 20 and 21. This has the effect of preventing vibration and attendant fatigue of the metal of the sinkers and dividers upon impact of their butts with the verge plate 36, thereby precluding ruptures and breakages of these elements such as frequently occur in machines of ordinary construction. During retreat of the sinkers and dividers as the stitches are being drawn it will be seen that by virtue of absence of the usual nebs of these elements, the friction upon the yarn is reduced to a minimum. This is obviously advantageous in that it precludes chaffing and ruptures of the yarn, and thereby not only enables production of fabrics from very fine yarns, but favors operation of the machine at higher speeds than practical heretofore.

The hereinbefore described welt bar controlling mechanism, and the new sinkers and dividers per se, have been made the subjects of separate applications.

Having discussed our invention, we claim:

1. In a straight knitting machine, a bar with a series of hook needles, a bar with needle-hook cover points to cooperate with the needles in stitch formation; supporting means for the point 75

bar rockable about a horizontal axis; means for rocking the point bar supporting means including a rotary cam; a spring biased follower arm arranged to be actuated by the cam, said arm being formed in two sections connected by a knuckle joint; and means operative at predetermined times during the knitting to break the knuckle joint of the arm and to prevent its actuation by the cam, and thereby preclude actuation of the point bar.

5 2. The combination according to claim 1, in which the knuckle joint breaking means includes a trip element normally out of the path of a projection on one of the sections of the follower arm beyond the knuckle pivot; and means for moving the trip element into the path of the lug when actuation of the point bar is to be prevented.

20 3. The combination according to claim 1, in which the knuckle joint breaking means includes a trip element pivoted on a fixed center and having a nose normally out of the path of a projection on one of the sections of the follower arm beyond the knuckle pivot, and wherein the means for operating the trip element moves it about its pivot to bring its nose into the path of 25 the lug when actuation of the point bar is to be prevented.

25 4. In a straight stocking knitting machine, a bar with a series of hook needles; a bar with needle hook cover points to cooperate with the needles in stitch formation; a substantially horizontal slide for supporting the point bar; a guide for the slide fulcrumed for oscillatory movement about a horizontal axis; a fixed stop abutment 30 constantly engaged by the slide to limit its inward movement in respect to the needles during normal knitting; means for yieldingly maintaining the slide normally engaged with the stop abutment; means for oscillating the guide for movement of the cover points into and out of operative relation to the needles in stitch formation; and means automatically operative during fashioning phases of the machine to retract the slide for withdrawal of the points, when in raised 35 position, out of the way of the needles.

40 5. In a straight stocking knitting machine, a bar with a series of hook needles; a bar with needle hook cover points to cooperate with the needles in stitch formation; a substantially horizontal slide for supporting the point bar; a guide for the slide fulcrumed for oscillatory movement about a horizontal axis; a fixed stop abutment 45 normally engaged by the slide to limit its inward movement in respect to the needles; means for yieldingly maintaining the slide engaged with the stop abutment; means for oscillating the guide for movement of the points into and out of operative relation to the needles in stitch formation, including a follower arm, and an endwise 50 shiftable shaft with a rotary cam thereon for normally actuating the follower arm; and means automatically operative during fashioning phases when the shaft is shifted to move the cam out of the plane of the follower arm, including a rocker 55 arm and another rotary cam on the cam shaft moved into the path of the rocker arm to actuate it when said shaft is shifted as aforesaid.

60 6. In a straight knitting machine, a bar with a series of hook needles; means for imparting up and down and press movements to the needle bar; a bar with a corresponding series of flexible needle hook cover points; and means operative during each stitch forming cycle to move the point bar from a retracted position for presentation of its points, with freedom to yield, at 65

the needles so as to be capable of flexing individually with the needles during the press movement of the needle bar.

7. In a straight knitting machine a fixed transversely-slotted head with a verge plate closing the tops of the slots; a series of longitudinally reciprocative butted sinkers in the slots of the head; a series of hook needles adapted to be moved up and down and laterally relative to the sinkers in stitch formation, said needles having shank portions equal in width to that of the intervals between sinkers; and a series of vertically-movable needle hook cover points likewise of a width corresponding to that of the intervals between sinkers, whereby as the needles and the cover points are moved into cooperative relation and the sinkers are slurred forwardly, the sink-

ers are prevented from vibrating upon impact of their butts with the verge plate.
